COVERED BUTTON

Sidney Mishkin, New York, N.Y., assignor to Bac-A-Brand Products, Inc., New York, N.Y., a corporation of New York

Filed Feb. 24, 1958, Ser. No. 716,956

4 Claims. (Cl. 24—104)

This invention relates to buttons, and more particularly to covered buttons.

The primary object of the present invention is to generally improve covered buttons, particularly button structures adapted to receive and hold a fabric covering. A more particular object is to devise such a button structure particularly intended for use in the home by those making their own dresses.

A more specific object is to devise such a button which requires no patterning of the fabric; which has large tolerance with respect to the thickness of the fabric; and which is of the "come-apart" type, that is, the button may be assembled or disassembled when desired. This facilitates cleaning or renewal of the fabric, while leaving the base portion of the button structure secured to the garment. Another advantage of the come-apart construction is that the button structure may be reused with a different fabric on a different or newly made dress.

To accomplish the foregoing general objects, and other more specific objects which will hereinafter appear, my invention resides in the come-apart button elements, and their relation one to another, as are hereinafter more particularly described in the following specification. The specification is accompanied by a drawing in which:

Fig. 1 is a section through the outer part of a button embodying features of my invention, with the rim in contracted condition;

Fig. 2 is a similar view but shows the top depressed and the rim expanded;

Fig. 3 is a perspective view showing the outer part of the button in expanded condition;

Fig. 4 is a perspective view showing how fabric may be wrapped around the outer part and tied;

Fig. 5 is a section similar to Fig. 1, but showing the outer and inner parts of the button assembled, with the fabric covering in place;

Fig. 6 is a section through a modified inner part;

Fig. 7 is a section through a modified inner part molded out of a plastics material;

Fig. 8 is a section through still another inner part molded out of a plastics material;

Fig. 9 is a perspective view of a different inner part, made out of sheet metal;

Fig. 10 is a section showing how a button using the inner part of Fig. 9 may be secured to a garment by means of a short nail-like fastener;

Fig. 10a is a plan view showing a modification of the inner part of Fig. 9;

Fig. 11 is a section through a modified form of outer part; and

Fig. 12 is a view similar to Fig. 11, but showing the top depressed to expand the rim.

Referring to the drawing, and more particularly to Fig. 5, I there show a come-apart button comprising an outer part 12 around which fabric 14 is wrapped and tied, as shown at 16. The procedure is better shown in Fig. 4, in which the fabric 14 has been tied at 16, but has not

2

yet been pushed upward by the inner part of the button. Reverting to Fig. 5, the outer part 12 receives an inner part 20 which is held within the outer part, and which itself serves to hold the fabric covering in position.

5 Referring now to Fig. 1, the outer part 12 has a convex circular top 22 and a rim 24 which is turned inward at its bottom edge 26. The rim and bottom edge are slit with multiple slits 28. The rim may be expanded by depression of the convex top, and referring to Fig. 2, it will be seen that the top 22 has been depressed with consequent spread or expansion of the bottom edge 26.

In the particular case here shown, the circular top 22 is a flat spring disc which moves abruptly to either side of a flat position. In other words, the metal is so contoured, dimensioned and treated that it is unstable in the center or flat position. Thus, when the top is pushed from the convex condition shown in Fig. 1 to the concave condition shown in Fig. 2, the edge 26 expands and remains in expanded condition. However, if the rim 24 is pressed inward, the top 22 is changed abruptly from the concave condition of Fig. 2 to the convex condition of Fig. 1, whereupon the bottom edge 26 remains in the contracted condition shown in Figs. 1 and 5.

25 The inner part 20 (Fig. 5) of the button is dimensioned to pass freely through the bottom edge when the rim is expanded as shown in Fig. 2, but it is held within the bottom edge 26 when the rim is contracted as shown in Fig. 5. It will be understood that the fabric 14 is stretched taut by the inner part 20 when the latter is pushed into the outer part, and indeed, this tensioning of the fabric may itself serve to pull the rim 24 inward, and so to return the concave top to its convex condition.

30 The button has fastening means to fasten it on a garment. In Fig. 5, the bottom of the part 20 has parallel slits near the center and the intermediate strip of metal is bent downward as shown at 30.

35 Referring now to Fig. 6, this shows a modified inner part 32. It resembles that previously described in being formed out of sheet metal, drawn to shallow cup shape. It differs only in respect to the fastening means 34, which in this case is a wire loop or eye, the ends of which are passed through small apertures in the bottom and are bent outward to hold the same in position as shown at 36. This provides a rounded surface to receive the sewing threads.

40 If desired, the inner part may be molded out of a suitable plastics material instead of being stamped out of sheet metal. Fig. 7 shows an inner part 40 which has been molded out of a plastics material. It is preferably hollow at the top, as shown at 42, in order to conserve the use of material; in order to lighten the button; and in order to provide adequate room to receive the excess fabric. A lug 44 is molded integrally with the inner part 40, and is apertured at 46 for sewing the button to a garment. The aperture may be formed as a part of the molding operation.

45 The inner part may be secured to the garment in other ways than by sewing, and in Fig. 8, I show an inner part 50 which is secured to a garment, schematically represented at 52, by means of a headed pin 54. The pin 54 has an enlarged or undercut head 56, as well as a flat base 58. Such a pin type fastening has already been used in solid uncovered buttons. The parts are assembled by pushing the pin through the fabric and into the button until the parts are received with a snap fit. This fastening is not intended to come apart again. The pin is made of yieldable material.

50 Another variant fastening means, best suited for use with a sheet metal inner part, is illustrated in Figs. 9 and 10 of the drawing. In this case, the drawn sheet metal

inner part 60 has crossed slits, shown at 62 and 64. The pin 66 has a relatively large flat base 68 somewhat like the head of a thumb tack. The pin is pushed through the garment material 70 and into a tiny hole formed at the intersection of the slits 62, 64. The sheet metal bends inward somewhat with passage of the pin, as shown at 72, and the four corners grip the pin and hold it against escape.

If desired, the shank of the pin may be roughened to improve the grip. It may also be threaded if it be desired to make the button removable, for in such case rotation of the pin will free the button.

In lieu of four corners to grip the pin, as shown in Fig. 9, the inner part may be slit in the form of an H, thereby providing two opposed tongues to grip the pin. Such a modification is shown in Fig. 10a of the drawing.

It will be understood that any of the different inner parts may be used with the outer part 12 described above. The inner part may be made of a metal or plastics material, or any other desired material, and the inner part, or the button as a whole, may be secured to the garment in any desired manner. The important thing here is that the inner part is dimensioned to pass readily into the outer part when the rim is expanded, and to be held by the outer part when the rim is contracted. The rim is provided with multiple slits to facilitate expansion and contraction, and is so associated with a convex top that depression of the top serves to expand the rim.

It is not essential that the top have an "over-the-center" or flat spring action. A modification which illustrates this is shown in Figs. 11 and 12 of the drawing. Referring to Fig. 11, the outer part 80 has a convex top 82 and a rim 84 which is turned inward at its bottom edge 86. The rim and bottom edge are slit with multiple slits 88. When the top 82 is depressed to the somewhat flatter condition shown at 82' in Fig. 12, the rim 84 and bottom edge 86 expand as shown at 84', 86'.

The inner part of the button may be constructed like any of those shown in Figs. 5, 6, 7, 8, 9 and 10a of the drawing. The inner part is not shown in Figs. 11 and 12, but its dimension has been indicated in dot-dash outline in order to better show the expansion of the outer part. Thus, in Fig. 12, the dot-dash rectangle 90 will readily pass the expanded bottom edge 86', but when pressure on the convex top 82' is relieved, permitting the top to assume its original convexity, as shown at 82 in Fig. 11, the bottom edge moves inward as shown at 86. It will then hold the inner part, as is schematically indicated by the dotted rectangle 90, which is confined within the contracted bottom edge 86.

It will be understood that the outer part shown in Fig. 11 differs substantially from that shown in Fig. 1, because the circular top is not an over-the-center or flat spring. It remains convex, but the degree of convexity is changed, and this concomitantly expands the bottom edge. When the bottom edge is expanded, it does not remain stably in expanded condition. It must be kept expanded by continued pressure. The structure is therefore not as convenient to use as that shown in Fig. 5.

The outer part shown in Figs. 11 and 12 is formed out of sheet metal. However, it will be understood that a similar structure may be molded out of a suitable plastics material, although in such case, the wall thickness is preferably increased, compared to the wall thickness when using sheet metal.

It is believed that the construction and method of use, of my improved covered button, as well as the advantages thereof, will be apparent from the foregoing detailed description. The piece of fabric used to cover the button need not be dimensioned and patterned in any particular way. It is simply drawn around the outer part and tied by winding a bit of thread thereabout. The excess fabric is then cut off by a single scissor stroke. Assembly of the button is completed by merely inserting the inner part. Because of the substantial expansion and

contraction of the slotted rim, the button is characterized by large tolerance in respect to the thickness of the fabric. The button may be disassembled as well as assembled, and that fact is of convenience, as when cleaning or changing the fabric, or reusing the button structure on a different garment.

It will be understood that while I have shown and described my invention in several different forms, changes may be made in the structures shown without departing from the scope of the invention, as sought to be defined in the following claims.

I claim:

1. A come-apart button adapted to be covered with fabric or the like, said button comprising an outer part directly around which the fabric may be wrapped, and an inner part adapted to be received and held within the outer part in order to hold the fabric covering in position, said outer part having a convex circular top and a slit rim which is turned inward at its bottom edge, said inner part being dimensioned to pass through the bottom edge when the rim is expanded, and to be held within the bottom edge when the rim is contracted, said rim being expanded by depression of the convex top, and said button having fastening means to fasten the assembled button on a garment, the convex circular top of the outer part being a flat spring disc which moves abruptly to either side of a flat position, whereby the slit rim remains expanded when the top is pushed from convex to concave condition, and the top is returned from concave to convex condition when the slit rim is pressed inward to contract it after assembly with the cloth and inner part.

2. A come-apart button adapted to be covered with fabric or the like, said button comprising an outer part directly around which the fabric may be wrapped, and an inner part adapted to be received and held within the outer part in order to hold the fabric covering in position, said outer part having a convex circular top and a rim which is turned inward at its bottom edge, said rim and bottom edge being slit with multiple slits, said inner part being dimensioned to pass through the bottom edge when the rim is expanded, and to be held within the bottom edge when the rim is contracted, said rim being expanded by depression of the convex top, and said button having fastening means to fasten the assembled button on a garment, the convex circular top of the outer part being a flat spring disc which moves abruptly to either side of a flat position, whereby the slit rim remains expanded when the top is pushed from convex to concave condition, and the top is returned from concave to convex condition when the slit rim is pressed inward to contract it after assembly with the cloth and inner part.

3. A come-apart button adapted to be covered with fabric or the like, said button comprising an outer part directly around which the fabric may be wrapped, and an inner part adapted to be received and held within the outer part in order to hold the fabric covering in position, said outer part having a convex circular top and a rim which is turned inward at its bottom edge, said rim and bottom edge being slit with multiple slits, said inner part being dimensioned to pass through the bottom edge when the rim is expanded, and to be held within the bottom edge when the rim is contracted, said rim being expanded by depression of the convex top, and said inner part having fastening means therebeneath to fasten the assembled button on a garment, the convex circular top of the outer part being a flat spring disc which moves abruptly to either side of a flat position, whereby the slit rim remains expanded when the top is pushed from convex to concave condition, and the top is returned from concave to convex condition when the slit rim is pressed inward to contract it after assembly with the cloth and inner part.

4. A come-apart button adapted to be covered with fabric or the like, said button comprising an outer part directly around which the fabric may be wrapped, and

an inner part adapted to be received and held within the outer part in order to hold the fabric covering in position, said outer part having a convex circular top and a rim which is turned inward at its bottom edge, said rim and bottom edge being slit with multiple slits, said inner part being dimensioned to pass through the bottom edge when the rim is expanded and to be held within the bottom edge when the rim is contracted, said rim being expanded by depression of the convex top, said convex top being a flat spring disc which moves abruptly to either side of a flat position, whereby the slit rim remains expanded when the top is pushed from convex to concave condition, and the top is returned from concave to convex condition when the slit rim is pressed inward to contract it after assembly with the cloth and inner part, said

inner part having fastening means to fasten the assembled button to a garment, and said fastening means including a pin having a head, a shank, and a base, with said pin adapted to be passed head first through a garment into a mating part of the button with a snap fit.
